ROLLING MILL

Edwin E. Moore, Gary, Ind., assignor to American
Sheet and Tin Plate Company, a corporation of
New Jersey

Application May 2, 1933, Serial No. 669,043

10 Claims. (Cl. 80—32)

This invention relates to metal strip cold rolling mills of the type having the strip arranged in a coil from which it is fed through a stand of rolls and recoiled. The operation may be reversing or not, and there may be more than one stand of rolls, in which case they will work in tandem.

Ordinarily the strip is coiled directly on spindles arranged adjacent both sides of the rolls and parallel their axes. These spindles' rotative speeds are controlled so that the strip enters and/or leaves the rolls under tension. When the rolling of a coil is finished it is removed by laterally sliding it from whichever spindle it happens to be on, this depending on the number of passes necessary to attain the desired gage and whether the mill reverses or operates in one direction.

The above is satisfactory when gages are heavy, widths are not great and the strip tensions are not sufficient to cause the coils to grip the spindles too tightly.

However, the rolling of wide metal strip to light gages and under heavy tensions is now being practiced, and the coiling of the strip directly on spindles has proven impractical because the coils grip too tightly, while the strip's edges are too fragile to permit the application of removal forces.

To meet the new conditions, modern mills are provided with coil centers which directly carry the strip coils and are bored for application to the spindles. That is, the strip is coiled on these coil centers to form units which may be slid on and off the spindles, the coils gripping these centers instead of the spindles.

Although this practice is generally effective, the great weights of these units necessitate their handling by unwieldy tractors or overhead cranes, this being slow, expensive and dangerous. Another objection is that the great strip tensions now being practiced sometimes create compressive forces which a coil center cannot withstand without partially collapsing, causing it to grip its carrying spindle so that it can only be removed by the use of excessive force, and often only by uncoiling the strip it carries.

Operators of mills of the type being discussed encounter still another difficulty. This is the maintenance of the parallelity of the spindles with respect to the working rolls, the heavy strip tensions being sufficient to force these spindles from their desired positions.

Two methods have been used to meet this difficulty. One is the setting of the spindles at slight angles and depending on the strip to draw them

parallel, and the other is the structural bracing of the free ends of the spindles.

The first method may be considered an expedient only, and has met with but partial success. The second method requires removable bearings carried by gate structures or the like so that the coils may be removed. These swinging structures are generally pivoted on the roll stand housing and must be very massive in construction. Naturally, they form undesirable obstruction to the mill operators in the conduct of their duties.

This brief summary of the strip cold rolling art is advanced as an aid in the appreciation of the present invention.

One of the objects is to handle rapidly the strip coils, whereby the continuity of rolling operations is more nearly attained. Another object is to mount the coils so their axes parallel those of the working rolls without incidentally obstructing the mill operators to any great extent, and to obviate the objectionable feature of a coil gripping its carrying spindle. Further objects include the provision of a generally new mill and rolling method.

The remainder of this specification illustratively discloses a specific form of the invention as required by the patent statutes, it being understood that the inventive scope is to be limited only as defined by the appended claims.

Referring to the drawings:

Figure 1 is a top plan of a mill embodying the present invention.

Figure 2 is a side elevation.

Figure 3 is a detail.

Figure 4 is a cross-section from the line IV—IV in Figure 3.

On each side of a 4-high roll stand is a reel drive consisting of a gear box 2 and a motor 3. These gear boxes 2 mount fluted stub shafts 4, instead of the customary spindles.

The metal strip is carried on reels 8 which each have journal ends 9 individually provided with permanently attached mounting bearings 10. The journal ends are fluted so they may be connected to the stub shafts 4 by internally fluted sleeves 11. These sleeves may be slid back and forth on the stub shafts 4.

Heavy hook-shaped brackets 12 mount the reels 8, by their bearings 10, parallel to the working rolls of the stand 1. These brackets are suitably braced from the roll stand and have their open faces arranged away therefrom.

Tracks 13 are arranged to register with the open faces of the brackets 12 so that the reels may be easily rolled thereinto. The tracks are 55

spaced to carry the reels by their mounting bearings, these being externally flanged and circularly surfaced to form what are, in effect, wheels. Preferably, the reels are prevented from free rotation by suitable locks 14 during their movement over these tracks. This may be necessary to prevent them skewing.

The tracks 13 may be prolonged somewhat on one side of the mill proper and stops 15 provided. 10 This forms a storage rack for reels of rolled strip. The tracks on the other side may be interrupted by right angular tracks 16 which carry a rough coil box 17 coupled to a reel carriage 18. A rough coil magazine 19 for hot strip may then be aligned 15 with these tracks, and other tracks 20 arranged parallel thereto and offset from the first tracks. By proper construction the mobile units may be pushed back and forth so that the rough coil box 17 can receive rough coils from the magazine 19 20 and feed them for their first pass through the mill, or the carriage 18 may be moved into registration with the first section of the tracks 13 to receive one of the reels 8 and carry it into registration with the second set of tracks 20.

25 In explanation of the above, these rough coils are those received from the hot strip mill and must be given their first pass through the mill for tight coiling on a reel on the other side. The rough coil box 17 is not specifically described because it may be constructed in the usual manner of those now being used.

The various movements are preferably effected by power, although they might be performed manually. For instance, the mobile rough coil 35 box 17 may be provided with a driving motor 21, and a pneumatic pusher 22 may be aligned with the tracks 20 to discharge the reels from the carriage 18.

It might also be here mentioned that pneumatic 40 pushers 23 are preferably arranged to discharge the reels from the brackets 12, and that suitable latching mechanisms 24 be provided these brackets to prevent the reels' accidental displacement while being coupled to the shafts 4 and 6 and their 45 carried strip fed through the mill.

The brackets 12 on both sides of the mill may be supplied with empty reels by raising and lowering tracks 25. These may also carry the empty reels by their bearings 10, and are suitably pivotally mounted above the tracks 13 by standards 50 26 for swinging movement of their free ends into registration with the faces of the brackets 12. They may be swung by any means, pneumatic motors 27 being illustrated merely as a suggestion. 55 These tracks 25 may not only feed empty reels to the brackets 12 when needed but may also receive empty reels therefrom.

Other details may include fluid cooled rolls 28 arranged on either or both sides of the mill 1 to 60 contact the passing strip. This will keep down the strip's temperature and prevent the usual troubles arising when it exceeds that of the working rolls. Suitable gage indicating means 29 are also preferably provided on both sides of the mill 65 for the roller's guidance. Such means may be flying micrometers, which may be arranged between the cooling rolls and the working rolls so that the increase in the coils' size will not affect their setting.

70 Preferably, the operator of this mill is provided with duplicate controls 30 which he may conveniently operate by standing on either of two 75 duplicate platforms 31 interconnected by a bridge 32 built over the driving spindles of the mill 1. It is to be noted that the entire mill consists of

duplicate parts on either side of the roll stand and grouped equally on either side of the center line thereof. Duplicate platforms and pulpits are provided for the mill operator because it is desirable that he be located so he may watch the outgoing metal to determine whether rolling operations are progressing satisfactorily. 5

The reels 8 must, of course, be provided with some means for clamping an end of the strip to be carried thereon. Preferably, this means 10 comprises a longitudinal slot 33 in which a jaw 34 is fitted. This jaw has a number of cam surfaces 35 on one of its sides which are engaged by cam surfaces 36 on the side of a longitudinally movable bar 37. When the bar 37 is moved the jaw 15 34 will be moved circumferentially in the reel and effectively clamp the end of the strip between itself and the side of the slot.

Operation of the mill is substantially as follows:

The mobile rough coil box 17 is moved into registration with the magazine 19. A rough loose coil of strip is then rolled from the magazine into this box and its end fed through the mill proper 1. The elevated swinging tracks 25 on the other side of the mill are then lowered and an 25 empty reel rolled into the bracket with which it registers. The latch 24 serves to hold this reel in place and the end of the strip may be placed between the side of its slot 33 and its locking jaw 34. Movement of the bar 37 to move these locking 30 jaws may be accomplished by striking it with a heavy object.

Now the strip is given its first pass through the roll stand and is tightly coiled on the empty reel. 35 Preferably, tension is applied to the exiting strip by properly controlling the speed of the motor 3 driving the receiving reel, this effecting the desired tight coiling.

When the above pass is completed an empty 40 reel is placed in the right hand bracket 12 from the tracks 25 there, and the end of the strip affixed thereto. The strip is now given a reverse pass and tightly coiled onto this second reel.

The strip is now given a number of passes back and forth from one reel to the other, until the 45 desired gage is attained.

Preferably, the motors 3 are constructed so they may act as brakes for the delivering reels, whereby the strip tensions are balanced on both the entering and exiting sides of the roll stand 1. 50 That is to say, when one motor is operating to draw the strip from the working rolls the other motor acts as a drag and thus balances the strip tensions. This diminishes or eliminates lateral displacement of the working rolls, such as is 55 prevalent when heavy tensions are applied to the exiting strip only.

The motors 3 may be wired for dynamic braking or to act as generators, this last enabling 60 a current saving because the motors may then be circulated to help power the motor driving the roll stand.

These various operations may all be performed 65 automatically by proper circuit arrangements effected by skilled mill electricians.

If the strip is given an odd number of passes the finished coil will be located in the left hand side of the mill. If this is so the latch 24 of the bracket is withdrawn and the pusher 23 operated to kick the loaded reel onto the tracks 70 75 13 over which it rolls to its end.

If the strip has attained the desired finished gage by having received an even number of passes it will be located on the right of the mill and is unloaded by a similar procedure onto the right 75

hand tracks 13. Here the rough coil box 17 is in the way. However, by operation of the motor 21 it is moved out of the way and the reel carriage 18 moved to a place where it can receive this reel. The motor 21 is again operated and the reel carried by this carriage into registration with the offset tracks 20. The pusher 22 is then operated to discharge the reel onto the tracks 20 where it may remain.

10 In either of the above instances the loaded reels are stored in out of the way places where they await the convenience of a craneman. If it is desired to carry them further these tracks may be prolonged and the reels rolled thereover 15 to other desired points. During all this rolling the reels' locks 14 are operated to prevent individual rotation of the bearings and reels.

It is obvious that the foregoing operations may be altered to suit differing conditions and that 20 the reels, whether loaded or unloaded, may be moved about generally without mutual interference and without the need of a crane and its attendant dangers. Also, the continuity of the rolling operations is practically unbroken in the 25 loading of successive strip lengths, because the various changes may be effected so rapidly.

I claim:

1. The combination of a stand of cold rolls, a plurality of reels individually provided with 30 mounting bearings and constructed to carry metal strip in coiled form, means on either or both sides of said stand for mounting said reels by their bearings for passing their carried strip through the stand, means for receiving and storing said reels from said mounting means, and means for delivering said reels to said mounting means, the third named means being arranged above the second named means at a sufficient height to permit functioning of the latter.

40 2. The combination of a stand of cold rolls, a plurality of reels individually provided with externally wheel shaped mounting bearings and constructed to carry metal strip in coiled form, means on either or both sides of said stand for mounting said reels by their bearings for passing their carried strip through the stand, tracks arranged for the rolling carriage of said reels by their mounting bearings and registering with said mounting means, and elevated tracks arranged 50 above the first named tracks so as to carry said reels and at a sufficient height to permit said rolling carriage of the latter.

3. The combination of a stand of cold rolls, a plurality of reels individually provided with 55 externally wheel shaped mounting bearings and constructed to carry metal strip in coiled form, means on either or both sides of said stand for mounting said reels by their bearings for passing their carried strip through the stand, tracks arranged for the rolling carriage of said reels by their mounting bearings and registering with said means, and raising and lowering tracks also arranged for the previously described carriage of said reels and also registering with said 60 mounting means when lowered.

4. The combination of a stand of cold rolls, a plurality of reels individually provided with externally flanged and circularly surfaced mounting bearings and constructed to carry metal strip 70 in coiled form, mounting brackets arranged on either or both sides of said stand and constructed for the lateral reception and engagement of said reels' bearings, tracks registering with said mounting brackets and arranged for the rolling carriage of said reels by their mounting bear-

ings, and swinging tracks also arranged for the rolling carriage of said reels by their mounting bearings and pivoted at elevated points for swinging motion of their free ends into registration with said mounting brackets.

5. The combination of a stand of cold rolls, a plurality of reels individually provided with externally flanged and circularly surfaced mounting bearings and constructed to carry metal strip in coiled form, means on either or both sides 10 of said stand for mounting said reels by their bearings for passing their carried strip through the stand, tracks arranged for the rolling carriage of said reels by their mounting bearings and leading away from registration with said 15 mounting means, raising and lowering tracks also arranged for the previously described carriage of said reels and registering with said mounting means when lowered, means alined with said tracks for holding metal strip in loosely coiled form, other tracks arranged similarly to the others and offset therefrom parallel to said means, means for rotatively mounting said loosely coiled metal strip movably interposed between 20 said first named tracks and said means for carrying metal strip in loosely coiled form, and means for carrying said reels from a point between said first named tracks and carrying means for metal strip in loosely coiled form to a point 25 registering with said other and offset tracks.

6. The combination of a stand of cold rolls, a plurality of reels individually provided with externally flanged and circularly surfaced mounting bearings and constructed to carry strip in coiled form, mounting brackets arranged on both 30 sides of said stand and constructed for the lateral reception and engagement of bearings, tracks arranged for the rolling carriage of said 35 reels by their mounting bearings and registering with said mounting brackets, and other tracks pivoted mounted above said first tracks for swinging movement into registration with said mounting brackets and arranged also to carry said reels as described.

7. The combination of a stand of cold rolls, a plurality of reels individually provided with externally flanged and circularly surfaced mounting bearings and constructed to carry metal strip in tightly coiled form, mounting brackets arranged on both sides of said stand and constructed for the lateral reception and engagement of 50 said reels' bearings, tracks arranged for the rolling carriage of said reels by their mounting bearings and registering with said mounting brackets, a magazine for holding metal strip in loosely coiled form alined with said tracks and spaced from one end thereof, other tracks arranged parallel to said magazine and offset from the tracks with which the latter is alined, means for rotatively holding metal strip in loosely coiled form 55 removably arranged between said magazine and the track set with which it is alined, means for carrying said reels from said tracks alined with said magazine to said tracks arranged parallel therewith, and other tracks pivotally mounted above said tracks registering with said mounting brackets and arranged for swinging motion of their free ends into registration therewith.

8. A strip mill comprising a fixed coil box, two parallel conveyers, one of which is in alinement 70 with said coil box but spaced therefrom, and transfer means for shifting devices laterally of said conveyers and relative to said coil box.

9. A strip mill comprising a fixed coil box, two parallel conveyers operable in opposite di-

rections for respectively supplying devices for said coil box and for transporting devices removed from said coil box, and transfer means for shifting devices from alinement with the sup-
plying conveyer into alinement with the other conveyer.

10. A strip mill comprising a fixed coil box.

a transfer car movable into and out of alinement with said coil box for supplying coil devices thereto, and two parallel conveyers having terminal portions adjacent the path of movement of said car for respectively supplying coil devices to said car and receiving coil devices therefrom. 5

EDWIN E. MOORE.
